HENRY D'OLIER, JR., OF BRIDGEPORT, CONNECTICUT.

REFLECTOR-HOLDER.

1,228,004.

Specification of Letters Patent.

Patented May 29, 1917.

Application filed March 28, 1916. Serial No. 87,160.

To all whom it may concern:

Be it known that I, HENRY D'OLIER, Jr., a citizen of the United States, residing at Bridgeport, county of Fairfield, State of Connecticut, have invented an Improvement 5 in Reflector-Holders, of which the following is a specification.

This invention has for its object to provide a reflector holder adapted for general 10 use and especially adapted for use in connection with porcelain lamp sockets. A further object of the invention is to provide a reflector holder which may be either permanently or detachably secured to the lamp socket, 15 which will hold the heaviest reflectors rigidly and securely, and which will permit the reflector to be removed without interference with the lamp socket.

With these and other objects in view, I 20 have devised the novel reflector holder which I will now describe, referring to the accompanying drawing forming a part of this specification and using reference characters to indicate the several parts:—

25 Figure 1 is an elevation showing my novel reflector holder in use;

Fig. 2 a section on the line 2—2 in Fig. 1, looking in the direction of the arrows, with the reflector removed;

30 Fig. 3 an elevation corresponding with Fig. 1, showing the locking members in the releasing position, and the reflector detached;

Fig. 4 an elevation on a reduced scale 35 showing another mode of attaching the holder to a lamp socket, and

Fig. 5 is a detail view on an enlarged scale corresponding therewith.

In Figs. 1, 2 and 3, 10 denotes a one-part 40 porcelain lamp socket, and 11 a shade or reflector. The neck of the reflector, or an extension by which it is carried, is provided with a groove 12 which is engaged by the holder. The special construction of the 45 socket is unimportant so far as the present invention is concerned. It is sufficient to say that the porcelain body of the socket is secured to a metallic cap 13 which in turn is secured to a tube 14 through which the electrical connections pass.

50 My novel holder comprises essentially a plurality of resilient locking members, in the present instance three, each formed from

a single piece of wire. The mid-length of the piece of wire is bent to form an arc-shaped gripper 15 which is adapted to pass into the groove in the neck of a reflector or extension and the curvature of which corresponds with the curvature of the neck at the base of the groove. At the ends of the 55 gripper, the wire is bent outward, as at 16, so as to clear the upper end of the neck, and is then bent upward and inward to form arms 17, the upper ends of the arms being bent inward at substantially 60 right angles and passed into holes 18 in the cap. A band 19 near the upper end of the porcelain body incloses the body and the arms tightly and retains the holder securely 65 in place. The locking members are of course 70 formed by automatic machinery and the wire is given a "set" which causes the locking members, when assembled, to normally spring outward radially, the grippers normally separating and springing outward far enough to disengage them entirely 75 from the groove in the neck, so that in the normal or releasing position of the locking members, as in Fig. 3, the neck of a reflector 80 or extension may be freely passed inward between the grippers or may be removed from between the grippers. As a means of 85 securely retaining the locking members in the locking position, I provide rings 20, each of which incloses the contiguous arms of two locking members. These rings when forced 90 downward on the arms, as in Fig. 1, act to draw the lower ends of the locking members inward radially and cause the grippers to pass into the groove in the neck and engage 95 the base of the groove firmly, thus locking the reflector rigidly to the holder. To release the reflector it is simply necessary to force the rings upward from the position shown in Fig. 1, toward that shown in Fig. 3. As soon as the rings are forced upward, 100 the resiliency of the locking members will cause them to again spring outward and release the reflector. It will be noted that in this form the weight of the reflector is carried by the cap, thus relieving the porcelain parts from strain and should they become broken, the reflector will still be supported.

The form illustrated in Figs. 4 and 5 differs only in the means of attaching the

holder to the lamp socket. The lower part of the socket is provided near its lower end with a groove 21 which receives the parts of a clamp 22. The parts are formed to an arc shape to fit the groove closely and are provided at their ends with ears 23 threaded to receive set screws 24 by which the parts are drawn together and closed tightly into the groove to lock the holder to the socket.

10 The locking members are made resilient and contiguous arms of two members are inclosed in rings, as before, which cause the locking members to grip or release a reflector. It will of course be obvious that

15 four or even more locking members may be used, if preferred. I find, however, that three locking members work admirably in use.

Having thus described my invention, I

20 claim:

1. A reflector holder adapted for attachment to a lamp socket and comprising a plurality of independent resilient locking members each formed from a single piece of wire, 25 the mid-length of which is bent to form an arc-shaped gripper, the wire at the ends of the gripper being bent outward to clear a reflector member as set forth, and then upward to form arms, means for attaching the 30 independent ends of the arms in fixed position to a lamp socket and rings inclosing the contiguous arms of two locking members, upward or downward movement of the rings causing the grippers to assume the releasing 35 or locking position.

2. The combination with a lamp socket and a reflector or extension having a grooved neck, of a holder comprising a plurality of independent resilient locking members, each 40 consisting of an arc-shaped gripper and arms, means for securing the independent ends of the arms in fixed position to the lamp socket and rings engaging the contiguous arms of two locking members, said 45 rings acting when pressed downward to cause the grippers to pass into the groove and lock the reflector in place.

3. The combination with a lamp socket member and a reflector member having a 50 groove, of a holder for supporting the reflector member with respect to said lamp socket member comprising a plurality of separate and independent locking members each having an arcuate portion adapted to 55 engage in said groove and arms extending longitudinally above and below said socket member, means for securing the upper ends of said arms in fixed relation with respect to said socket member, and members engaging 60 neighboring arms of neighboring locking members and movable longitudinally for drawing said arcuate portions into said groove.

4. The combination with a lamp socket 65 member and a reflector member, of a holder

for supporting said reflector member with respect to said lamp socket member comprising a plurality of separate and independent locking members each consisting of an integral piece having an arcuate engaging portion, upwardly extending arms at the ends of the arcuate portion, a cap secured to said socket member and having apertures receiving the inturned ends of said arms, and members engaging neighboring arms of neighboring locking members and movable longitudinally thereof for causing said arcuate portions to engage said reflector member.

5. The combination with a lamp socket member and a reflector member, of a holder for supporting said reflector member with respect to said lamp socket member comprising a plurality of separate and independent locking members each consisting of an integral piece having an arcuate engaging portion, outwardly extending portions at the ends of said arcuate portion, upwardly extending arms at the ends of said outwardly extending portions, means securing the upper ends of said arms to said lamp socket member, and members engaging neighboring arms of neighboring locking members and movable longitudinally thereof for causing said arcuate portions to engage said reflector member.

6. The combination with a lamp socket member and a reflector member, of a holder for supporting said reflector member with respect to said lamp socket member comprising a plurality of separate and independent resilient locking members, each comprising an arcuate portion, longitudinally extending arms at opposite ends of said arcuate portion, a cap secured to said lamp socket member, the free ends of said arms secured by said cap, and members engaging and movable longitudinally of arms of neighboring locking members to bring said arcuate portions into engagement with said reflector member.

7. The combination with a lamp socket member and a reflector member, of a holder for supporting said reflector member with respect to said lamp socket member comprising a plurality of separate and independent resilient locking members, each comprising an arcuate portion, longitudinally extending arms at opposite ends of said arcuate portion, a cap secured to said lamp socket member, the free ends of said arms secured by said cap, members engaging and movable longitudinally of arms of neighboring locking members to bring said arcuate portions into engagement with said reflector member, and a circumferential band engaging said arms.

8. The combination with a porcelain lamp socket member, of a metallic cap to which said member is secured, a reflector member,

a holder for supporting said reflector member with respect to said lamp socket member comprising a plurality of separate and independent resilient members each comprising an arcuate portion, upwardly extending arms extending inwardly above said lamp socket member and held by said cap, and

members engaging and movable longitudinally of said arms of neighboring resilient members for causing said arcuate portions 10 to engage said reflector member.

In testimony whereof I affix my signature.

HENRY D'OLIER, JR.
